HANGER FOR SIGNS OR OTHER OBJECTS

Fred Charles Beseler, Shreveport, La.

Application December 19, 1938, Serial No. 246,658

3 Claims. (Cl. 40—138)

This invention relates to improvements in methods of erecting and hanging signs and other objects suspended from an overhanging or horizontal circular, or half circular, support.

5 The objects of the improvement are, first, that on many occasions it becomes necessary to hang and suspend from a horizontal circular, or half circular, support a sign, lamp, light or other objects, and it is necessary to grant these objects 10 a limited swing movement, and second, it becomes necessary to formulate some device which will stabilize the position of these objects and at the same time absorb the shock of heavy wind pressure and other climatic conditions that may cause 15 such signs or other objects to start a swinging motion, and third, this device will be inexpensive to construct, simple and efficient to install.

The particular features of the invention will be pointed out in the claims at the end of the specification.

20 Figure 1 shows a full side elevation of the hanger device in relation to sign or other objects and the horizontal support which also shows angle bars rigidly attached to the sign F which upper 25 portions of the said angle bars rest upon the hollow pipe E and between the sides of frame B and the hollow pipe E passes through the lower part of the angle bars and the sign F as shown in said drawing.

30 Figure 2 shows a side elevation of a hanger device showing a slot in the upper part of frame or yoke through which horizontal part of vertical post extends.

Figure 3 shows a sectional view of a side elevation of the frame or yoke with its relation to the base of the vertical post which is attached to the horizontal circular, or half circular, support, which shows a slot in the frame or yoke through 35 which the base of the vertical post extends in attaching to horizontal circular, or half circular, support.

40 Figure 4 shows a top sectional view of the frame or yoke showing a slot in frame or yoke through which the base of vertical post extends in attaching to horizontal support.

45 Figure 5 shows how part of the frame or yoke may be changed to support a single flat object.

Part A is a piece of strap iron with two slots in the upper portion forming the outer part of 50 the frame or yoke.

Part B is a piece of strap iron formed in a U shape, having a slot in the curved portion and bolt holes in open ends which form inside and lower part of frame or yoke.

55 Part C is a combination of bolt, flat iron, and

rod welded together and being the vertical post attached to the horizontal support, the said part forming a T shape.

Part D is a coil tension spring but could be rubber or any other resilient means confined between the vertical post and each arm of the frame or yoke.

Part E is a section of hollow pipe used as a spacer between the open ends of the lower part of the frame or yoke.

Part F is a sign or object having an angle frame.

Part G is the horizontal circular or half circular support.

Part H is a flat sign or object with no frame.

My hanger comprises a piece of heavy strap iron B, or other strap material of sufficient strength, which is curved around the circular part of rod G, and has two arms of the same length extending down which are securely attached to sign F. The curved end of B is provided with a rectangular slot through which extends the lower end of vertical post C, which is rigidly secured to rod G, thereby, giving B and F the opportunity of a limited swing movement. A piece of strap iron is securely attached to the upper outside part of each of the arms of B and is bent slightly outward from each arm then is extended upward parallel with the vertical post C. The two upward extended arms of A are connected by a cross bar at the top forming a frame as shown in the drawing, for the purpose of supporting and making rigid the upward extended arms of A. The upper ends of the extended arms or frame of A are provided with rectangular slots so that the laterally extended rods which are rigidly attached to the top of post C may pass through and permit a coil spring, rubber or other resilient means D, which is imposed around the laterally extended arms of C and is confined in a stationary position, between the upper part of post C and the upper inside walls of extended arms or frame of A to absorb the shock and creating a smooth resistance to the swinging movement of F, B, and A, which may be caused by wind or other forces.

The swinging movement of F, B, and A which are all attached together causes the upper part of A to move closer to vertical post C, which at all times occupies a stationary position and thereby creates a compression of the spring or other resilient means which limits and resists the swinging movement in a smooth manner and eliminates all possibility of sudden shock which has here-

tofore caused considerable damage to swinging signs.

I claim:

1. A hanger including, a support, a vertical post extending upwardly from the support, a frame adapted to be mounted on the support so as to be capable of a limited swinging movement and having an indicia carrying element suspending therefrom, upwardly extending arms on the frame and disposed on opposite sides of the post, and resilient means confined between the post and each arm for normally holding said frame in a vertical position and also for absorbing shock when the frame is swung.
- 5 10 15 20
2. A hanger including, a horizontally extending support, a vertical post extending upwardly from the support, an inverted U-shape frame engaging over the support and adapted to swing thereon, said frame having a slot through which the post extends, upwardly extending arms on the frame

and disposed on opposite sides of the post, and resilient means confined between the post and each arm for normally holding said frame in a vertical position and also for absorbing shock when the frame is swung.

3. A hanger including, a horizontally extending support, a vertical post extending upwardly from the support, an inverted U-shape frame engaging over the support and adapted to swing thereon, said frame having a slot through which the post extends, upwardly extending arms on the frame and disposed on opposite sides of the post, a guide bar extending through the upper end of the post and also through the arms, said bar being 10 15 20

slidable with relation to the arms, and coiled springs surrounding the bar and confined between the post and each arm for normally holding the frame in a vertical position and for absorbing shock when the frame is swung.

FRED CHARLES BESELER. 20
